(57) **CLAIM**

The ornamental design for a buoy, as shown and described.

DESCRIPTION

FIG. 1 is a front view of a buoy, showing my new design, with the back view being identical thereto;

FIG. 2 is a front view of the design shown in FIG. 1;

FIG. 3 is a top view of the design shown in FIG. 1; and,

FIG. 4 is a bottom view of the design shown in FIG. 1.

The features shown in broken lines in the drawings are included for the purpose of depicting portions of the buoy and form no part of the claimed design.

1 Claim, 3 Drawing Sheets
